UNITED STATES PATENT OFFICE

JOSEPH A. HODEL, OF CUMBERLAND, MARYLAND.

CHIMNEY.

SPECIFICATION forming part of Letters Patent No. 363,236, dated May 17, 1887.

Application filed July 30, 1886. Serial No. 209,532. (No model.)

To all whom it may concern:

Be it known that I, JOSEPH A. HODEL, of Cumberland, in the county of Alleghany and State of Maryland, have invented a new and useful Improvement in Chimneys, of which the following is a specification.

My invention relates to chimneys, comprising certain details in the construction of a device with a view of rendering it effective in action, simple in construction, and readily applicable to the building in connection with which it is to be used.

In the accompanying drawings, Figure 1 is a vertical sectional view of a portion of a building provided with my device. Fig. 2 is a horizontal section taken on line $x-x$, Fig. 1. Fig. 3 is a detail sectional view taken on line $y-y$, Fig. 2; and Fig. 4 is a sectional view showing manner of applying my chimney to new buildings or to buildings not having brick flues.

In the drawings, A represents the ordinary brick flue. In the top of this flue, and just below the roof, I securely "build in" a metallic casting, C, having lateral flanges c . It is also provided with an offset, c' , about midway of its vertical portion, and it is also extended at its top at right angles and provided with the vertical flanges c^2 , passing up to the roof 30 of the building, as shown.

It will be seen that the body portion of the casting forms a continuation of the flue B. Resting in offset c' is a short flue-section, D, having a flaring mouth, d, at its top and provided with the perforated cover e. It will be seen that by this arrangement sparks and cinders are effectually prevented from exit at top of chimney and fall back into bottom of flue, from whence they may be readily removed.

The flue D extends beyond the roof, and is surrounded by an outer casing, E. This casing extends below the roof, and is held in place by the vertical flange c^2 and dowel-pins e' and angle-plate e^2 , as shown. This angle-plate or gland fits snugly against the bottom of the outer casing, and is cemented or otherwise secured to the roof, thus forming a tight joint. Casing E is surmounted by an ornamental metal top, F. This top is preferably 50 of the form shown in the drawings, and is provided with the smoke-exit f. This top is

provided on three of its sides with downward-projecting flanges, and on two of its sides it is provided with tongues g , sliding in grooves g' in the upper portion of casing E.

By reference to Figs. 2, 3 it will be seen that the tongues project beyond one end of casing E, and are there provided with a perforation, into which is fitted a key or pin, l, as shown. By this arrangement the top can be readily applied and securely held in place. At the end of the top not having the downward-projecting flange the top of casing E is extended, as at m, Figs. 2, 3, thus preventing an access of air, which would otherwise occur at this point. The parts D, E, and F are preferably made of metal.

The operation of applying my device is as follows: When it is desired to place my improvement on chimneys already in use, the same may be applied by untopping the chimney to within a short distance beneath the roof. The casting C is then securely built in the top of the chimney and the parts D, E, and F secured thereto, as will be readily understood.

In Fig. 4 I have shown the method of applying my device to new buildings or to buildings not having brick flues. In this case I form the flue in sections, $b-b' b^2$, each section having telescopic ends and provided with lateral flanges n , and fastened by the bolts or rivets o , the casting C secured to the upper section, b^2 , as shown. The lower section, b' , is enlarged, as shown, and affords ready access for cleaning the flue. Branch flues a extend from main flue B, as shown.

By constructing the chimney as described it will be seen that the same can be easily put up and securely fastened. It effectually prevents the danger of fire by protecting the portions of the building next the chimney, and also presenting a neat and ornamental top.

Having thus described my invention, what I claim as new is—

1. A chimney-top consisting of a casting provided with an internal offset and a lateral extension at its top, having an upwardly-projecting flange, a flue-section supported upon the offset of the casting and provided with a perforated cover, a casing supported upon the lateral extension of the casting, and an aper-

- tured cap secured to said casing, substantially as herein shown and described.
2. The combination, with the casting C, provided with the offset c' and a lateral extension 5 having the flange c'' , of the flue-section D, supported upon the offset of the casting and provided with the perforated cover e, and a casing supported upon the lateral extension of the casting, substantially as herein shown and de-
10 scribed.
3. In a chimney-top, the combination, with the casing E, having the grooves g' in its upper end, of the cap F, provided with the

tongues g , fitting in the grooves of the casing, substantially as herein shown and described. 15

4. In a chimney-top, the combination, with the casing E, having the grooves g' in its upper end, of the cap F, provided with the tongues g , projecting beyond the casing and perforated, and the pins l , inserted in the said 20 perforations, substantially as herein shown and described.

JOSEPH A. HODEL.
